UNITED STATES PATENT OFFICE.

MAUNSELL C. WAKEFIELD, OF DALLAS, TEXAS, ASSIGNOR TO DALLAS ICE FACTORY,
OF DALLAS, TEXAS.

COUPON BOOK.

Application filed December 9, 1922. Serial No. 605,827.

To all whom it may concern:

Be it known that I, MAUNSELL C. WAKEFIELD, citizen of the United States, residing at Dallas, in the county of Dallas and State 5 of Texas, have invented certain new and useful Improvements in Coupon Books, of which the following is a specification.

This invention relates to new and useful improvements in coupon books.

10 The object of the invention is to provide means for ascertaining at a glance the value or number of coupons remaining in a book which has been in use and to do so without opening the book.

15 The invention is particularly applicable to ice coupon books which contain pages, each divided into a number of detachable coupons arranged to be torn off transversely of the page. In such an arrangement each 20 coupon is printed with a designation indicating the value or number of the coupons remaining in the book after the preceding coupon has been removed and the cover is provided with openings or windows for exhibiting said designation, so that the highest 25 amount or number exhibited thru said windows may be easily ascertained.

30 A construction designed to carry out the invention together with other novel features will be hereinafter described.

35 The invention will be more readily understood from a reading of the following specification and by reference to the accompanying drawings, in which an example of the invention is shown and wherein:

Fig. 1 is face view of a coupon book embodying the invention, which is shown in a closed position,

40 Fig. 2 is an inside view of the same showing one of the coupons detached,

Fig. 3 is a vertical sectional view on the line 3—3 of Fig. 1, and

45 Fig. 4 is a fragmentary view of the lower portion of the book showing that coupons have been removed and indicating the value of those remaining.

In the drawings the numeral 10 indicates 50 the cover of an ordinary coupon book and 11 the back thereof. It is customary to print the name of the firm and other advertising matter on the face of the cover, together with other data. Where the book is used for ice it is the practice to number the book

on the face of the cover and also to indicate the total number of pounds for which the 55 book is issued.

Within the book are bound a plurality of pages composed of separable or detachable coupons 12, each bearing a designation 13 indicating the number of pounds of ice for 60 which the coupon will be redeemed. Each coupon may also bear the same number as appears upon the cover.

I have shown four coupons to the page 65 each good for twenty-five pounds of ice, but both the number of coupons to the page the value thereof may be varied. In carrying out the invention it is of course desirable that each coupon have the same unit value. Each coupon is printed with a 70 numeral or other designation 14 and these are arranged in successive order in the same sequence in which the coupons are to be detached.

The numerals 14 are printed at the same 75 location on each coupon and the cover 10 is provided with a plurality of openings or windows 15 positioned so that the said numerals will register therewith, there being a separate window for each numeral 14. 80

I have shown a book issued for five hundred pounds of ice and therefore the first page of coupons will exhibit thru the windows the numeral 500 at the lowermost window and the numbers 475, 450 and 425, 85 successively to the top. One glancing at the cover of the book would see that the largest number was 500 and therefore no coupons had been removed. In Figs. 2 and 4 I have shown a book in which some of the coupons 90 have been removed and the bottom coupon of the front page having been detached. The coupons above the detached coupon exhibit the numbers 375, 350 and 325, while the bottom coupon of the next page which 95 is exposed exhibits the numeral 300.

One looking at the cover of the book 100 would see these numbers thru the windows 15 and 375 being the highest, would indicate that coupons good for 375 pounds, still remained in the book. When the last page was reached the numbers 100, 75, 50 and 25 would be exhibited thru the windows and it would be seen by both the customer and the dealer or iceman, that the book was 105 nearly exhausted.

It is customary to hang these books on the wall and by the use of my invention one may determine at any time by a mere glance, just how much remains in the book, just 5 how many coupons the iceman removes and when it is necessary to purchase a new book. It also forms a check at the office of dealer as after each delivery the coupon bearing the successive numeral 14 should be 10 brought in.

Various changes in the size and shape of the parts as well as modifications may be made within the scope of the appended 15 claims.

15 What I claim, is:

1. In a coupon book, a cover having spaced 20 openings, and detachable coupons in the book each having a value designation adapted to register with one of the openings, whereby the highest designation may be observed thru one of the openings.

2. In a coupon book, a cover having spaced 25 openings, pages of coupons in the book, there being a separate opening for each coupon, and each coupon having a value designation 30 registering with the opening for said coupon, the value designations of the cou-

pons on each page diminishing in value upwardly of the page.

3. In a coupon book, a cover having spaced 30 openings, pages of coupons detachable in said book, there being a separate opening for each coupon on a page, each coupon being printed with a value designation indicating the value of the coupons remaining 35 in the book after the preceding coupons have been detached, each value designation registering with one of the openings, whereby the value of the coupons remaining undetached may be observed at a glance. 40

4. In a coupon book, a cover having spaced 45 openings, pages of coupons detachable in said book and each having a like unit of value and each coupon being printed with a value designation of one unit less than the preceding coupons and equal to the combined value of all the coupons remaining 50 in the book after the preceding coupons have been detached, there being an opening for each coupon of a page and each value designation registering with one of the openings.

In testimony whereof I affix my signature.
MAUNSELL C. WAKEFIELD.
